(57) CLAIM

The ornamental design for a combined writing instrument holder and bookmark, as shown and described.

DESCRIPTION

FIG. 1 is a front perspective view of a combined writing instrument holder and bookmark;

FIG. 2 is a rear perspective thereof;

FIG. 3 is a right side view thereof;

FIG. 4 is a left side view thereof; and,

FIG. 5 is a perspective view in its intended environment.

The broken lines showing two writing instruments and a book in FIG. 5 are for environmental purposes only and form no part of the claimed design.

1 Claim, 3 Drawing Sheets
